Inventor John E. Weaver.

United States Patent Office.

JOHN E. WEAVER, OF NETHER PROVIDENCE TOWNSHIP, PENNSYLVANIA.

Letters Patent No. 95,293, dated September 28, 1869.

IMPROVEMENT IN BRAN-DUSTER FOR FLOUR-MILLS.

The Schedule referred to in these Letters Patent and making part of the same.

To all whom it may concern:

Be it known that I, JOHN E. WEAVER, of Nether Providence township, Delaware county, Pennsylvania, have invented certain new and useful Improvements in Bran-Dusters; and I do hereby declare that the following is a full and exact description of the same, reference being had to the annexed drawings, forming part hereof, in which drawings—

Figure 1 represents an elevation of the brush-cone, brushes, and fan, and a vertical section of the other parts of the machine.

Figure 2, a perspective of the brush-cone, brushes, and fan, enlarged and detached.

Figure 3, in perspective, a modification of the fan, enlarged.

My improvements are designed to effect a draught of the materials to be acted upon by the machine, from the top toward the bottom of the brush-cone, and thus to bring into efficient action the whole brush-surface of the wire cloth.

They consist in arranging the brushes at an angle with the cone-shaft, and in the employment, in connection with brushes so arranged, of a fan, placed below the brushes, in the chamber enclosed by the wire cloth.

Referring to the drawings—

In fig. 1, *a* represents the frame of the machine.

b, the brush-cone.

c, the shaft which passes through and rotates said cone, the lower end of which shaft bears upon the adjustable step *d*.

The brushes *e* are arranged on said cone at an angle of, say, from ten to twelve degrees from the plane of shaft *c*.

f represents the wire cloth, which is fastened to a frame consisting of upper and lower rims, *g* and *h*, and connecting-ribs *i*, the latter being in sufficient number to hold the wire cloth to its position.

k, figs. 1 and 2, is the fan, which is attached to the shaft *c* by set-screws.

I prefer to give as many plates or leaves, *m*, to the fan as there are brushes employed, and to set the leaves so that they correspond with the angle of the brushes.

The leaves *m* are each provided with a slot, *n*, through which, by means of set-screws, the lower ends of the brushes respectively are secured in position.

The brushes, at their upper ends, are attached to the slotted lugs *p* by set-screws, as shown in figs. 1 and 2.

q, fig. 1, are sweeps, by which the flour, brushed through the wire cloth *f*, is caused to run down the exit-spout *r*.

s is the pulley by which power is applied to shaft *c*. Instead of attaching the fan as represented in figs. 1 and 2, I prefer, however, to attach it in the manner represented in fig. 3, wherein *t* and *u* represent two rings, which slide on shaft *c*, to which they are secured by set-screws.

Each ring is provided with arms *v*, to which the fan-leaves are attached by set-screws, which pass through slots in the fan-leaves, as shown.

The fan-leaves are provided with other slots, *w*, for the set-screws by which the lower ends of the brushes are secured.

This method of constructing the fan facilitates the adjustment of the brushes, when it is desired to change their draught, that is to say, the angle of their inclination to the shaft.

I prefer to use four brushes in a machine intended to dust the bran produced by two sets of stones, and six brushes in a machine intended for four sets of stones.

The frame of the machine may be six and a half feet high by two and a half feet square, the cone sixteen inches in diameter at the larger end, and six inches at the lower or smaller end; the fan six inches in depth.

The bran to be dusted drops down, through spout *x*, on the top plate *y* of the cone, and is thrown to the periphery of said plate by centrifugal force, and passes down between the brushes and the wire cloth, being impelled by the draught of the brushes, and drawn by the partial vacuum formed at the bottom of the cone, by the action of the fan.

Having thus described my invention, I claim, and desire to secure by Letters Patent— The brushes herein described, when arranged upon the cone, at an angle with the line of the shaft, as and for the purposes specified.

JOHN E. WEAVER.
